UNITED STATES PATENT OFFICE.

EDWIN G. BUSSE AND ERNEST A. LE BEAU, OF CHICAGO, ILLINOIS, ASSIGNORS TO
CHICAGO RAILWAY EQUIPMENT COMPANY, OF CHICAGO, ILLINOIS, A CORPOR-
ATION OF ILLINOIS.

ROLLER SIDE BEARING.

1,148,144.

Specification of Letters Patent. Patented July 27, 1915.

Application filed May 16, 1914. Serial No. 839,014.

To all whom it may concern:

Be it known that we, EDWIN G. BUSSE and ERNEST A. LE BEAU, citizens of the United States, residing at the city of Chicago, county of Cook, and State of Illinois, have invented a certain new and useful Improvement in Roller Side Bearings, of which the following is a full, clear, and exact description, such as will enable others skilled in the art to which it appertains to make and use the same, reference being had to the accompanying drawings, forming part of this specification, in which—

Figure 1 is a side elevational view partly in vertical section of my improved roller side bearing for railway cars. Fig. 2 is a bottom view partly in horizontal section. Fig. 3 is a vertical cross sectional view. Fig. 4 is an end view.

This invention relates to side bearings for railway cars of the single roller type, and embodies in its general organization a casing equipped with movable carriers or followers, a roller disposed between said followers, a removable axle carrying said roller and engaged with the followers, and means, preferably in the form of springs, acting upon the followers to maintain the roller normally in centered position.

The invention has for its objects to provide a simplified form of device, the parts of which may be readily assembled or dismantled; one wherein the axle may be readily inserted or removed to effect assembling or disconnection of the parts; one in which a simplified means is provided for preventing accidental displacement of the axle and consequent accidental dismantling of the bearing; and one in which the lateral movement or play of the axle in a horizontal plane relative to the transverse axis of the casing is overcome.

With these and other objects in view the invention comprises the novel features of construction and combination of parts more fully hereinafter described.

While there is shown an inverted bearing designed for attachment to the body bolster of the car it is obvious that this bearing could be attached to the truck bolster, in which event the roller would be presented upwardly and the casing provided with dirt exits preferably disposed in line with the surface of the track plate.

In the drawings, 1 designates a casing

having an upper base portion or wall provided at its ends with perforated attaching lugs or ears 2, there being secured to the inner face of said wall, and within the casing a track plate 3, preferably of hardened steel. The side walls of the casing are provided with inwardly presented guide ways or grooves 4 extended longitudinally of the casing and formed to receive movable carriers or follower blocks 5 provided with projecting centering portions or fingers 5 adapted to receive and form bearings for the adjacent ends of centering springs 7 seated at their opposite ends in seats or pockets 8 formed in the walls of the casing. The bearing blocks or followers 5, are each made in a single piece provided at its center with a bearing opening 8' there being employed a pair of the bearing blocks slidably mounted one in each of the guide ways 4.

9 is an axle whose ends are mounted in the bearing opening 8' provided in the blocks 5, and 10 is the roller mounted on the axle between the bearing blocks and coöperating with the track plate 3. The periphery of this roller extends beyonds beyond the plane of the edges of the side walls, the casing being provided at a point opposite the track plate with a suitable longitudinal opening through which the roller is thus exposed. One of the side walls is provided with a bossed opening in which a removable key plug 11 is arranged, said key plug being held in position by a cotter 12. The inner face of the key plug is preferably flush with the inner face of the groove 4 with which its opening communicates, and the size of this opening is such as to permit the introduction and removal of the axle 9. The other side wall is provided with an opening 13 preferably opposite plug 11 so that when it is desired to dismantle the structure a small driving tool may be inserted through said opening 13 to drive out the axle. As illustrated, the openings 8' in blocks 5 in which the axle operates, may be somewhat elongated for the purpose of permitting free spinning movement of the roller and slight vertical movement of the roller independently of the carriage.

In assembling the parts of the bearing above described, the bearings 5 and springs 7 are first introduced, after which the roller is placed between the bearings and the axle then inserted. The key plug is now intro-

duced to close the opening through which the axle was inserted and the cotter pin introduced to prevent displacement of the key plug.

- 5 It is to be particularly noted that, as illustrated in Figs. 1 and 2, the opening through which the axle 9 is introduced, in the operation of assembling the parts, is in axial alinement with the horizontal line of movement of the axle 9 within the guide ways, but is eccentric to the vertical axis of said axle when in normal centered position. Owing to this disposition of the opening relative to the normal position of the axle, 10 it obviously becomes necessary to move the bearing blocks to an abnormal position for permitting introduction of the axle into place while under normal conditions, and after the parts have been properly assembled any end thrust of the axle will be borne in part by the side wall of the casing, thus to prevent accidental displacement of the axle. Displacement of the axle and accidental dismantling of the parts is positively prevented by means of the closure 11 seated and secured within the opening through which the axle is introduced, it being noted that owing to the inner end of this plug or closure being flush with the 15 inner surface of the guide way 4 the latter is rendered continuous in a smooth unbroken plane to present a smooth surface upon which the adjacent bearing block 5 may ride.
- 20 35 It is to be further observed that owing to the bearing blocks being made in one piece, as distinguished from constructions in which such blocks are each composed of two pieces or sections, the axle is provided 40 with firm bearings for its ends and is thus maintained in proper axial alinement with the transverse axis of the casing.

Although we have shown a form employing but one roller, it is evident that the carriage may be formed to carry two or more

rollers mounted and operating therein in fashion similar to the one shown.

We claim:

1. In a side bearing for railway cars, a casing provided with longitudinal guide ways, followers arranged for movement in said guide ways and having bearing openings, a roller disposed in the casing between the guide ways, an axle removably mounted in the roller and having its ends seated respectively in said bearing openings, said casing being provided with an opening through which the axle is introduced into place, this opening being registerable with the axle in said guide ways at a certain point in its travel but to one side of the axis of the axle when in normal centered position, and means acting on the followers for normally centering the roller.

2. In a side bearing for railway cars, a casing having longitudinal guide ways, followers arranged for movement in the guide ways, a roller disposed between the followers, a removable axle carrying said roller and having bearing at its ends in the followers, said casing having a lateral opening through which the axle is inserted or removed for assembling or dismantling the device, said opening being registerable with the axle in the guide ways to one side of the normal centered position thereof, a closure for said opening having its inner face flush with and forming an unbroken continuation of the inner surface of the adjacent guide way, and means for maintaining the roller normally in centered position.

In testimony whereof we hereunto affix our signatures in the presence of two witnesses, this 12th day of May, 1914.

EDWIN G. BUSSE.
ERNEST A. LE BEAU.
